CLAIM

The ornamental design for an eraser holder, as shown and described.

DESCRIPTION

FIG. 1 is a left side elevational view of an eraser holder showing my new design;

FIG. 2 is a front elevational view;

FIG. 3 is a right side elevational view;

FIG. 4 is a rear elevational view;

FIG. 5 is a top plan view;

FIG. 6 is a bottom plan view;

FIG. 7 is a left front perspective view; and

FIG. 8 is a front elevational view thereof, with the extended eraser portion being shown in broken lines for illustrative purposes only and forming no part of the claimed design.

FIG. 1   **FIG. 2**   **FIG. 3**   **FIG. 4****FIG. 5****FIG. 6****FIG. 7****FIG. 8**
